UNITED STATES PATENT OFFICE.

WILL R. PORTER, OF PRINCE BAY, NEW YORK, ASSIGNOR TO THE S. S. WHITE DENTAL MANUFACTURING COMPANY, A CORPORATION OF PENNSYLVANIA.

DENTAL-ENGINE HANDPIECE.

1,391,906.

Specification of Letters Patent. Patented Sept. 27, 1921.

Application filed September 23, 1920. Serial No. 412,333.

To all whom it may concern:

Be it known that I, WILL R. PORTER, a citizen of the United States, and a resident of Prince Bay, county of Richmond, State of New York, have invented certain new and useful Improvements in Dental-Engine Handpieces, of which the following is a specification, reference being had to the accompanying drawings.

10 My invention relates particularly to that class of handpieces in which a tool-engaging chuck is actuated by a relative axial movement of certain of the handpiece parts, and which is commonly known as "pull-out" and 15 "wedge" type.

It is well known that this type of handpiece as heretofore constructed when extended axially to clamp the tool by actuation of the clutch, a portion of the slide or 20 back spindle bearing is necessarily exposed, and it is difficult, if not impossible, for the operator to prevent contact of the hand with the oily surface of such exposed portion.

The principal object of my invention is to 25 provide a handpiece of such simplified construction as to render possible the provision of means to prevent contact of the operator's hand with the interior parts thereof.

Other objects of my invention are to provide 30 a handpiece with a front spindle and a back spindle or driving shaft, which may be operatively connected by interlocking members formed on the adjacent ends of the back spindle and wedge slide, to afford a substantially universal joint, and arranged to be 35 engaged and disengaged by a lateral relatively sliding movement of said part into and out of axial alignment.

My invention further comprehends novel 40 means for engaging the handle section or sheath with the union section or collet, and for adjusting said sheath thereon and determining its axial position.

Specifically stated, the form of my invention 45 as hereinafter described, comprehends a handpiece comprising a front spindle connected through the wedge slide with the back spindle or shaft by a T-head and undercut socket joint; a slide or bearing for said 50 back spindle or shaft, having its rear end enlarged to provide an annular head; a union section or collet forming a sleeve or

pushing embracing said slide or bearing; a sheath in threaded engagement with said collet, the axial position of the sheath being determined by a split nut also in threaded engagement with said collet and adjustable thereon; and a tubular shield removably attached to said head and supported thereby in telescopic relation with said sheath.

My invention also includes all of the various novel features of construction and arrangement as hereinafter more definitely specified.

In the accompanying drawings, Figure 1 is a central longitudinal sectional view of a handpiece constructed in accordance with my invention; Fig. 2 is a similar central longitudinal sectional view of said handpiece having its relatively movable parts axially extended to clamp the chuck on the tool; Fig. 3 is a fragmentary perspective view of the universal connection between the driving shaft and wedge slide or coupling; Fig. 4 is a fragmentary sectional view taken axially of said handpiece on the line 4-4 in Fig. 1, and showing the substantially universal connection between the driving shaft and wedge slide or coupling; Fig. 5 is a transverse sectional view taken through the oil chamber on the line 5-5 in Fig. 1; and Fig. 6 is a transverse sectional view taken on the line 6-6 in Fig. 1.

In said figures, the handpiece comprises the forward tubular spindle 1 engaged by the wedge slide or coupling 2 with the back spindle or driving shaft 3, and arranged to be rotated thereby within the casing comprising the tubular sheath or hand-hold 4 which is slidably mounted on the back spindle bearing or slide 5 by its threaded connection with the sleeve or collet 6 which is mounted to slide longitudinally on said bearing or slide 5.

The sleeve or collet 6 is in threaded engagement with the rear end of the sheath 4, and, therefore, may be adjusted axially therein and retained in such adjusted position by the sheath adjusting lock nut 7 which is also in threaded engagement with said sleeve or collet 6.

The driving shaft bearing or slide 5 is conveniently provided with the keyway 9

into which the collect key 10 in the collet 6 may extend to prevent the relative rotation of said collet 6 and slide 5, but permitting their free relative movement in an axial or 5 longitudinal direction.

The slide 5 has its rear end enlarged to provide an annular head 12 having the forwardly extended threaded boss 13 which conveniently carries the tubular shield 15. 10 extended forwardly and disposed in telescopic relation with the sheath 4 and serving as a protection to the exposed oily exterior surface of the slide 5 when the sheath 4 is extended with respect to said slide 5 to 15 clamp the tool as hereinafter described.

Said head 12 is also provided with a rearwardly extended threaded boss 16 arranged to carry a slip joint ferrule or a cable sheath of well known construction, and said boss 20 16 is provided with a recess 20 arranged to receive the back spindle collar 21 which is secured to the back spindle or driving shaft 3 by the set screw 22. The rear end 23 of the back spindle or driving shaft 3 is reduced and provided with screw threads 24 arranged to receive the end of a flexible driving cable of well-known construction. 25

The forward end of the back spindle or driving shaft 3 is enlarged to form the 30 cylindrical head 25 and is provided with the undercut transversely extending slot 26, which is arranged to receive the T-headed projection 27 of the wedge slide or coupling 2 fitted therein with sufficient looseness to 35 afford a substantially universal joint whereby the rotation of the back spindle or driving shaft 3 effects the rotation of said wedge slide or coupling 2.

Said wedge slide 2 is provided at its forward end with the projecting key or spline 40 extending into a suitable slot or keyway 30 in the wall of the forward spindle 1 which is mounted for rotation in the sheath 4. The forward end of said forward spindle 1 is supported in the conical bearing 33, and the back end is arranged to rotate in the bearing provided by the cylindrical sheath bushing 34, mounted in the recess 35 in the wall of the bore of said sheath 4. An end 45 thrust bearing washer 36 is disposed in the bore of the sheath 4 and affords an end thrust bearing for the forward spindle 1.

The forward spindle 1 is provided with the transversely disposed slot 37 intersecting 50 the slot 31 and serving as a bearing for the trunnions 39 of the lever 40, which is disposed for oscillation in the slot 41 in the wedge slide or coupling 2, and which has its free end inclined to bear against the serrated wall 42 of said slot, so that said free end may engage any one of the serrations and serve to lock the parts of the handpiece in their relatively adjusted positions 55 when extended, as shown in Fig. 2.

60 The lever 40 is arranged to effect the

clamping of the tool 45 in the chuck 46, which is longitudinally split and provided at its opposite ends with conical surfaces respectively arranged to bear against similarly inclined conical surfaces 47 and 48, 70 respectively formed in the bore of the forward spindle 1, and in the bore of the plunger 49, which carries the plunger tip 50 arranged to be engaged by the elbow 51 of the lever 40 so that when the relatively slideable members of the handpiece are shifted to cause the lever 40 to ride upon the serrated wall 42, the elbow 51 forces the plunger 49 forwardly against the chuck 46 and by coöperation of the conical ends of said 75 chuck with the conical surfaces 47 and 48 it is contracted to embrace the tool 45 therein with such pressure as to firmly hold said tool in its operative position. 80

The collet 6 is provided with the oil hole 85 52 which registers with a suitable opening 53 in the slide 5 for the injection of oil into the annular chamber 55 between the driving shaft 3 and its bearing in the slide 5, formed by the reduced region 56 of said 90 driving shaft 3. Said oil hole 52 is normally covered by the sheath 4, and is accessible by the mere removal of said sheath. 95

The head 12 of the slide 5 is conveniently provided with the aperture 57 into which a 95 bodkin or other suitable tool may be inserted for holding said head when it is desired to remove or separate the handpiece parts by relative rotation.

It will be readily seen that the slightest 100 wear of the parts in their bearings may be taken up by loosening the sheath-adjusting nut 7 and rotating the sheath 4 on the collet 6 until the adjustment of the bearings is attained, which adjustment may be maintained by jamming the sheath-adjusting nut 105 7 into engagement with the end of the sheath 4. Said sheath nut 7 may preferably be split as shown at 60 and by its spring pressure tightly clamps the collet 6. 110

My invention is advantageous in that the parts of the handpiece may be taken apart and assembled by the removal of a single set screw 22 and the sheath 4 which permits the withdrawal of the back spindle or driving 115 shaft 3 from its bearing in the slide 5, and when thus released from said bearing, the wedge slide 2 may be separated from said back spindle or driving shaft 3 by simply sliding them oppositely in a lateral direction to release the T-head 27 on said wedge slide 2, from the undercut slot 26 in the head 25 of the back spindle or driving shaft 3. 120

Furthermore, by the construction herein contemplated, the space between the relatively slideable members is bridged by the shield 15 so as to protect the oily exterior surface of the slide 5, and thereby prevent the hands of the operator from being soiled by contact therewith. 125 130

I do not desire to limit my invention to the precise details of construction and arrangement as herein set forth, as it is obvious that various modifications may be made 5 therein without departing from the essential features of my invention as defined in the appended claims.

Having thus described my invention, I claim:—

- 10 1. A dental engine handpiece having a shield arranged to prevent contact of the operator's hand with the interior parts thereof.
- 15 2. A dental engine handpiece having a sheath and a shield in telescopic relation with the sheath, arranged to prevent contact of the operator's hand with the interior parts thereof.
- 20 3. A dental engine handpiece having a sheath, and relatively movable members arranged to actuate a tool-holding clutch, and a shield carried by one of said members in telescopic relation with said sheath.
- 25 4. A dental engine handpiece having a front spindle and a back spindle or shaft, the adjacent ends of said spindles being provided with interlocking members embodying means tending to maintain them substantially coaxial when rotated one by the other and arranged to be readily connected and disconnected.
- 30 5. A dental engine handpiece having a front spindle and a back spindle or shaft, a connection between said spindles comprising a T-head and a socket, forming an interlocking joint whereby said front spindle may be rotated by said back spindle or shaft.
- 35 6. A dental engine handpiece having a front spindle and a back spindle or shaft, the adjacent ends of said spindles being joined by interlocking members arranged

to be readily connected and disconnected by a relative sliding movement laterally.

7. A dental engine handpiece comprising a front spindle connected with the back 45 spindle by a T-head and socket joint, a casing or bearing for said back spindle, having its rear end enlarged to provide an annular head, a collet or sleeve embracing said bearing, a sheath in threaded engagement with 50 said collet, and a tubular shield carried by said head in telescopic relation with said sheath.

8. A dental engine handpiece comprising a front spindle connected with the back 55 spindle or shaft by a T-head and socket joint, a casing or bearing for said shaft having an annular head, a collet or sleeve embracing said bearing, a sheath in threaded engagement with said collet, a nut also in 60 threaded engagement with said collet adjustable thereon to determine the axial position of said sheath, and a tubular shield removably attached to said head and supported thereby in telescopic relation to said 65 sheath.

9. A dental engine handpiece comprising a driving shaft, a bearing for said driving shaft having an oil chamber surrounding said shaft and provided with an inlet, a 70 collet embracing said bearing, and having an oil aperture in registry with said inlet, and a sheath in threaded engagement with said collet arranged to close said aperture.

In witness whereof, I have hereunto set 75 my hand this 21 day of September, A. D. 1920.

WILL R. PORTER.
